UNITED STATES PATENT OFFICE.

WILLIAM C. ANDERSON, OF TOLEDO, OHIO, ASSIGNOR TO THE W. L. LIBBEY
& SON COMPANY, OF SAME PLACE.

DESIGN FOR THE ORNAMENTATION OF GLASSWARE.

SPECIFICATION forming part of Design No. 19,076, dated May 7, 1889.

Application filed January 21, 1889. Serial No. 297,101. Term of patent 7 years.

To all whom it may concern:

Be it known that I, WILLIAM C. ANDERSON, a citizen of the United States, and a resident of Toledo, in the county of Lucas and State of Ohio, have invented a certain new and original Design for the Ornamentation of Glassware; and I do hereby declare that the following is a full, clear, and exact description of the design, which will enable others skilled in the art to which it appertains to make and use the same, reference being had to the accompanying drawings, and to the letters of reference marked thereon, which form part of this specification.

15 The class to which this design relates is that of ornamentation of glassware, and the design pertains to the ornamentation of the exterior surface thereof.

The drawings represent, in Figure 1, a bottom plan view of a dish containing the design, and in Fig. 2 a transverse section on lines α α , Fig. 1.

20 The design is applicable to any kind of glassware, such as bowls, plates, jugs, and dishes.

The leading features of my design are obovate projections formed by intersecting curvilinear lines, each projection being embellished with a rhomb and a central prismatic stud 25 having a checkering of miniature diamonds. The central portion of the bottom of the dish is an octagon, A, formed by a series of curvilinear lines, B, extending from the upper edge of the dish and curving toward the bottom thereof. Each curvilinear line B crosses four like lines of curvature, thereby forming 30 obovate projections C, each obovate pro-

jection having a rhombic ornamentation, D, formed therein by reason of prisms E, cut marginally of the same. Each rhomb is embellished with inscribed triangles F and a central prismatic stud, G. Below the series of rhombs just described is formed an encircling row of prismatic studs, H, with angular 40 projections I upon the sides and below the same, upon which is a checkering of miniature diamonds. The octangular figure formed upon the bottom is embellished with rows of prisms tangential to a central prismatic stud, K. In the spaces between the octangular 45 figure and the crossing of the curvilinear lines B are formed pyramidal projections L.

The ornamentation herein described harmonizes with the shape of the dish and gives a pleasing symmetry to the same. 50

What I claim is—

The design for the ornamentation of glassware herein described and shown, the same consisting of the intersecting curvilinear lines upon the side thereof, forming obovate projections, embellished with a rhomb having inscribed triangles and a central prismatic stud, with a lower prismatic stud surrounded upon three sides by angular projections having a checkering of miniature diamonds, as 60 set forth.

In testimony that I claim the foregoing as my own I hereby affix my signature in presence of two witnesses.

WILLIAM C. ANDERSON.
